[57] **ABSTRACT**

An antistatic softening composition, comprising 4-10

percent by weight of a quaternary ammonium salt of general formula (I):

wherein R₁ and R₂ each represent an alkyl group of C₁₄-C₂₂, R₃ and R₄ each represent an alkyl group of C₁-C₃, benzyl group or -(C₂H₄O)_nH (n = 1-3) and X represents Cl, Br or C₂H₅SO₄, 0.1-5 percent by weight of an ethenoxy quaternary ammonium salt of general formula (II):

wherein R₅ represents an alkyl group of C₁₀-C₂₂, R₆ represents an alkyl group of C₁-C₃ or benzyl group, X represents Cl, Br or C₂H₅SO₄ and m and n each represent an integer of more than 1 inclusive, with the proviso that m + n is 20-100, and 0.5-15 percent by weight of one or more additives selected from the group consisting of alcohols of lower than C₃ inclusive, glycols, glycerol, sorbitol and urea.

**ANTISTATIC SOFTENING COMPOSITION
CONTAINING A QUATERNARY AMMONIUM
SALT AND A ETHENOXY QUATERNARY
AMMONIUM SALT**

BACKGROUND OF THE INVENTION

1. FIELD OF THE INVENTION

The present invention relates to a softening composition which is stable even at a high concentration and which imparts an excellent antistatic property to the treated textile products. 10

2. DESCRIPTION OF THE PRIOR ART

Softening agents have been used frequently as finishing agents for textile products. They are used mainly for finishing of washed underwear and diapers to impart a soft feeling to the textile products. Important properties required of softening agents are as follows: 15

- a. to impart a soft feeling to the treated textile products,
- b. to impart antistatic property to the treated textile products,
- c. not to reduce hygroscopicity of the treated textile products, and
- d. to maintain stability and low viscosity even at a high concentration of the softening agent solution against possible environmental changes.

Among the above four properties, (a) is indispensable of course and most important, while properties (b) through (d) are also significant in practice. 30

Various compositions of softening agents have been known, but most of them contain quaternary ammonium salts having two long chain alkyl groups as their main ingredients.

Further, some of the known compositions contain, in addition to said main ingredient, a nonionic surfactant such as an alkylphenol ethylene oxide adduct and a solvent such as an alcohol or glycol to improve the stability of the solution. Although satisfactory softening effects can be obtained by using such known compositions, the properties (c) and (d), particularly the antistatic property and stability of them are still insufficient. 40

Recently, the use of fabrics for clothing made of synthetic fibers has been increasing more and more. However, as compared with fabrics of natural fibers, they have serious shortcomings in that they are apt to have a static electric charge, which results in dusty clothing, clinging of the clothing to the body and sparking at the time of putting on or pulling off of the clothing. These serious shortcomings of synthetic fiber clothing fabrics are well known.

Further, during the storage of softening agent solutions under various climate and temperature conditions, an increase in the viscosity of the solution or a phase separation is undesirable. In addition, it is desired that the softening agents do not freeze at a low temperature around the freezing point, or even if they are frozen, their viscosities are recovered when the temperature is elevated again to room temperature. 55

It is expedient to incorporate an antistatic agent for obtaining a composition having an antistatic property. However, if a conventionally known antistatic agent such as stearyl trimethylammonium chloride is incorporated in a softening agent composition containing a quaternary ammonium salt having two long chain alkyl

groups as the main ingredient, the stability of the aqueous solution is lowered markedly so as to make the solution useless, though some antistatic effect can be obtained. Further, a useful, stable aqueous solution cannot be obtained by using a long chain alkylmethyl-dipolyoxyethylene ammonium chloride containing 2-15 moles of ethylene oxide, a well known antistatic agent. 5

SUMMARY OF THE INVENTION

The present invention relates to a softening composition having an excellent softening effect, particularly a sufficient stability even at a high concentration, and an excellent antistatic effect upon treated textile products. 15

The present invention relates to an antistatic softening composition characterized by containing 4-10 percent by weight of a quaternary ammonium salt represented by the following general formula (I):

wherein R_1 and R_2 each represent an alkyl group of $C_{14}-C_{22}$, R_3 and R_4 each represent an alkyl group of C_1-C_3 , benzyl group or $-(C_2H_4O)_nH$ ($n=1-3$) and X^- represents Cl^- , Br^- or $C_2H_5SO_4^-$, 0.1-5 percent by weight of ethenoxy quaternary ammonium salt represented by the following general formula (II):

wherein R_5 represents an alkyl group of $C_{10}-C_{22}$, R_6 represents an alkyl group of C_1-C_3 or benzyl group, X^- represents Cl^- , Br^- or $C_2H_5SO_4^-$ and m and n each represent an integer of more than 1 inclusive, with the proviso that $m+n$ is 20-100 and 0.5-15 percent by weight of one or more additives selected from the group consisting of alcohols of lower than C_3 inclusive, glycols, glycerol, sorbitol and urea.

Now a description will be made of particularly preferred compositions. Preferred R_1 and R_2 are $C_{16}-C_{18}$ alkyl groups and preferred R_3 and R_4 are C_1-C_3 alkyl groups and benzyl group. Preferred R_5 are those of $C_{12}-C_{18}$ and the sum of m and n is preferably 30-70. Preferred additives are propylene glycol, ethylene glycol and glycerol. The preferred amount of the ethenoxy quaternary ammonium salt of the above general formula (II) is 1.0-5.0 percent by weight and the preferred amount of the additives is 3-8 percent by weight. The most preferred quaternary ammonium salts of the above general formula (I) are distearyl dimethylammonium chloride and dihydrogenated tallowalkyl dimethylammonium chloride. Though the object of the invention can be attained sufficiently with the above composition without any other additives, a small amount of an inorganic salt such as $NaCl$, $NaBr$, or Na_2SO_4 , usually 0.01 to 0.5 percent by weight, is 55

preferably incorporated therein for ensuring the stability of the composition for a long period.

The present invention will be illustrated more concretely by way of examples.

EXAMPLE 1

(This example is to demonstrate the effects based on the constituents of the compositions.)

Among the compositions shown in Table 1 given below, the compositions A through G are those of the present invention and the compositions H through K are comparative ones. Percentages in the table are shown in weight and the remainder is the amount of water.

Viscosity, antistatic property and softening property shown in Table I are measured according to the methods which will be described below. The results of the measurements are shown by four grades of $\bigcirc$, $\bigcirc$, Δ and $\times$, $\bigcirc$ being the most excellent (the lowest in viscosity). Quaternary ammonium salts in the table are compounds of the general formula (I) and the ethenoxy quaternary salts are ethenoxy quaternary ammonium salts of the general formula (II). The symbol "EO" indicates ethylene oxide.

METHODS OF MEASUREMENT

1. Viscosity:

The composition directly after blending was allowed to stand at room temperature for 6 months and then at 50° C for 3 months, frozen at -30° C, thawed at room temperature and then frozen again. This procedure was

repeated 5 times. Four samples of each composition were measured at 30° C with Brookfield type viscometer. The unit of numerals in the table is centi-poises.

2. Antistatic property:

5 Every swatch made from polyester fiber or acrylic fiber was immersed in 0.1 percent or 0.3 percent solution of each softening composition (weight ratio of the composition to the treating solution = 1:20) and it was stirred and treated for 5 minutes. The solutions were
10 squeezed out at 100 percent squeeze ratio. The swatches were dried and then allowed to stand at 25° C under 40 percent humidity for 2 days to obtain the samples. The results of frictional static voltage measured with a rotatory static tester (the model by the
15 Chemical Laboratory for Kyoto University) are shown in Table 2. Generally, at a frictional static voltage of less than 300 V, a drawback due to the static electricity is negligible. In this connection, frictional static voltages of untreated swatches of polyester and acrylic fibers were 2,200 V and 1,900 V, respectively.

3. Softening property:

Pieces of cotton towel, cotton plain fabric for diaper and blanket made from polyacrylonitrile fiber were washed in a usual manner, treated with 0.1 percent and 0.3 percent solutions of each softening composition and finally dried. The samples were tested by 5 men and 5 women according to handling (tactile impression) and their feelings were evaluated by the points compared with the standard criteria. The numerals in Table 2 are the sums of the points. The larger the numeral, the softer the textile.

Table 1

Composition	Quaternary ammonium salt (%)	Ethenoxy quaternary salt or another quaternary salt (%)	Additive (%)		Viscosity	Antistatic property	Softness

EXAMPLE 2

(This example is to demonstrate the effects based on the proportions of constituents of the compositions.)

Effects of changes in the ethylene oxide units of ethenoxy quaternary salts and effects of additives (such as propylene glycol) were examined to obtain the results as shown in Table 3.

Composition:

Distearylmethylammonium chloride	7.0%
Stearylmethyldipolyoxyethylene ammonium chloride (containing 2-120 moles of ethylene oxide)	2.5% or none
Propylene glycol (PG)	0-20%
NaCl	0.02%
Water	remainder

METHODS OF MEASUREMENT:

1. Viscosity

The composition immediately after the blending was allowed to stand at room temperature for one month

and measured at 30° C with a Brookfield type viscometer. The unit of numerals in the table is centi-poises.

2. Recovery after freeze

The samples were frozen by allowing them to stand at -25° C for one day, and thawed by elevating the temperature to a room temperature. This procedure was repeated five times and the state of the samples was examined.

3. Dispersion stability

The samples were allowed to stand in a constant temperature bath at 50° C for one month and the phase separation was examined.

The results of evaluation of the above items (2) and (3) were shown by four grades (in the same manner as in Example 1).

The same tendency as in Table 3 was observed also with other ethenoxy quaternary salts, i.e., behenylmethyldipolyoxyethylene ammonium ethosulfate and laurylbenzylmethyldipolyoxyethylene ammonium chloride. In Table 3, the numerals in the column 1 indicate the numbers of the ethylene oxide unit in 1 mole of the molecule and those in the line 2 indicate wt. percent of PG added.

The embodiments of the invention in which the exclusive property or privilege is claimed are defined as follows:

1. An antistatic softening composition, consisting essentially of 4-10 percent by weight of a quaternary ammonium salt of the formula (I):

(I) 10

wherein R_1 and R_2 each represent an alkyl group of $C_{14}-C_{22}$, R_3 and R_4 each represent an alkyl group of C_1-C_3 , benzyl group or $-(C_2H_4O)_nH$ ($n = 1 - 3$) and X represents Cl , Br or $C_2H_5SO_4$, 0.1-5 percent by weight of an ethenoxy quaternary ammonium salt of the formula (II):

(II)

wherein R_5 represents an alkyl group of $C_{10}-C_{22}$, R_6 represents an alkyl group of C_1-C_3 or benzyl group, X represents Cl , Br or $C_2H_5SO_4$ and m and n each represent an integer of more than 1 inclusive, with the proviso that $m + n$ is 20-100, 0.5-15 percent by weight of

one or more additives selected from the group consisting of alcohols of lower than C_3 inclusive, glycols, glycerol, sorbitol and urea, the balance of said composition being water.

2. An antistatic softening composition according to claim 1, in which R_1 and R_2 each represents an alkyl group of $C_{16}-C_{18}$, R_3 and R_4 each represents an alkyl group of C_1-C_3 or benzyl group, R_5 represents an alkyl group of $C_{12}-C_{18}$ and the sum of m and n is 30-70.

3. An antistatic softening composition according to claim 1, in which the additive is selected from propylene glycol, ethylene glycol and glycerol.

4. An antistatic softening composition according to claim 1, in which the amount of said ethenoxy quaternary ammonium salt of the formula (II) is 1.0 to 5.0 percent by weight.

5. An antistatic softening composition according to claim 1, in which the amount of the additive is 3 to 8 percent by weight.

6. An antistatic softening composition according to claim 3, in which the amount of the additive is 3 to 8 percent by weight.

7. An antistatic softening composition according to claim 1, in which said quaternary ammonium salt of the formula (I) is selected from distearyldimethylammonium chloride and dihydrogenated tallowalkyl dimethylammonium chloride.
